UNITED STATES PATENT OFFICE.

JAMES M. HARRUB AND HOMER N. TYSON, OF HONOLULU, TERRITORY OF HAWAII;
SAID TYSON ASSIGNOR TO SAID HARRUB.

VALVE-CAGE REMOVER.

Application filed April 16, 1923. Serial No. 632,467.

To all whom it may concern:

Be it known that we, JAMES M. HARRUB and HOMER N. TYSON, citizens of the United States, residing at Honolulu, Territory of Hawaii, have invented certain new and useful Improvements in a Valve-Cage Remover, of which the following is a specification.

This invention relates to an improved tool for facilitating the quick and expeditious removal of valve cages from motors having valves of the overhead type, the improved tool being so constructed, that the entire valve assembly can be removed, without injury thereto or to the cylinder head.

Another object of the invention is to provide an improved tool for pulling or removing valve cages of overhead valves from motors, which can be readily placed in position in engagement with the valve for facilitating the removal of the valve assembly from the cylinder head, the tool being so arranged as to permit the use thereof by the layman, without the necessity of employing a skilled mechanic.

Another object of the invention is to provide a valve cage remover, which can be used to the best advantage by mechanics, and which will considerably simplify their work in the handling of overhead valve assemblies in Buick and other automobiles.

A still further object of the invention is to provide a valve cage remover for automobile motors employing overhead valves which can also be used to the best advantage for temporary grinding valve seats and loosening any carbon which might be adhering to the valve and seat or cage.

A still further object of the invention is to provide an improved valve cage puller of the above character, which will be durable and efficient in use, one which will be simple and easy to manufacture and which can be placed upon the market at a reasonable cost.

With these and other objects in view the invention consists in the novel construction, arrangement and formation of parts, as will be hereinafter more specifically described, claimed and illustrated in the accompanying drawings, in which drawings:

Figure 1 is a side elevation of the improved valve cage puller showing the same partly in section and in use for pulling a valve cage, the cylinder head and valve assembly being shown in cross section.

Figure 2 is a horizontal section taken on the line 2—2 of Figure 1.

Figure 3 is a horizontal section taken on the line 3—3 of Figure 1.

Figure 4 is a bottom plan view of the 60 puller plate.

Figure 5 is a transverse vertical section through the improved valve cage pulling tool showing the same applied to a cylinder head.

Figure 6 is an enlarged fragmentary section through a portion of the tool showing the use of swivel seats for lifting screws in lieu of the U-shaped bearing plates.

Figure 7 is a side elevation of the key 70 utilized for turning the valve stem, the key being shown partly in section and applied to the upper end of a valve stem.

Figure 8 is a fragmentary section of the key or wrench applied to the upper end of 75 the valve stem.

Figure 9 is a detail horizontal section taken on the line 9—9 of Figure 7 illustrating the means of connecting the key or wrench with the valve stem.

Referring to the drawings in detail, wherein similar reference characters designate corresponding parts throughout the several views, the letter A generally indicates the improved valve cage pulling tool 85 and B a motor with which the same can be used.

The motor B can of course be of any preferred type embodying overhead valves and as shown for example a Buick motor is 90 illustrated, which includes the cylinder head 10 having the usual way 11 for the valve cage 12. The valve cage 12 is held in position in the ordinary manner, that is by a threaded ring, fitted into the threaded end 13 of the said way 11. The valve cage 12 is of the ordinary construction and slidably supports the stem 14 of the valve 15. The upper end of the stem is provided with the ordinary type of cross pin 16 which bears 95 against the upper washer 17 for the expansion spring 18, which is coiled about the said valve stem 14. The lower end of this spring seats on the lower washer 19.

The improved tool A embodies an upper pulling plate 20, which as shown is substantially of U-shape when viewed in plan and includes end portions 21 and 22 and the arcuate connecting body portion 23 which is adapted to encircle the valve stem 110

14. Now the inner edges of the end portions 21 and 22 and the connecting arcuate body portion 23 are provided with a rabbeted portion 24 defining a flange 25, on which is 5 adapted to seat the upper washer 17, when the valve cage or the complete valve assembly is to be pulled from out of the way 11. The forward end of the flange or shoulder 25 at the lower surface thereof is inclined as at 26 to define a knife edge inserting point 27 and it is obvious that when the pulling plate 20 is placed in position that these edges 26 engage between the upper end of the valve spring 18 and the washer 17 and thus facilitate the positioning of the plate in position. The valve spring being adapted to seat under the plate, while the washer is adapted to seat upon the shoulder or flange 25.

20 The end portions 21 and 22 are provided with threaded ways 28' for the reception of the lifting cap screws 28 and 29. The lower ends of these cap screws are provided with ball bearing ends 30, which are adapted to engage either removable swivel feet 31 or the U-shaped bearing plate 32. The U-shaped bearing plate 32 is utilized where an uneven surface is encountered, while the swivel feet 31 are utilized where flat surfaces are encountered.

The bearing plate 32 is of a flat construction and is shaped similar to the pulling plate 20 and also includes the end portions 33 and 34 and the connecting arcuate body portion 35 which is adapted to encircle the valve spring 18 and stem 14. The end portions 33 and 34 are provided with sockets 36 which are adapted to be positioned in the ball bearing ends 30 of the cap lifting screws 28 and 29.

40 A key or wrench 40 is also used with the improved tool, and as shown this key or wrench 40 embodies a shank 41 having the diametrically extending handle 42 arranged with its upper end to facilitate the turning of said shank. The lower end of the shank 41 is provided with a head 43 for receiving the upper end of the valve stem 14 and this head is slotted diametrically 50 as at 44 for the reception of the valve key 16.

The handle 42 is preferably disposed below the upper end of the shank for a purpose, which will be hereinafter more fully described.

55 In use of the improved tool, when it is desired to pull the cage 12 or the entire valve assembly, the bearing plate 32 or the feet 31 as the case may be, are placed upon the upper surface of the cylinder head, 60 after which the bearing plate 20 is placed in position between the valve spring 18 and the washer 17, as heretofore described until the ball heads or bearing members 30 fit in the sockets 36 of the plate 32 or in the bearing feet 31. The key 40 can now be

used and is inserted over the valve stem 14 and the stem is turned until the pin 16 comes in direct alignment with the adjusting or lifting cap screws 28 and 29.

The cap screws 28 and 29 are now rotated alternately for raising the puller plate 20 and it is obvious that the raising of this plate will pull the cage from the way 11.

70 It is to be understood of course that prior to the pulling of the way that the retaining screw threaded ring is now threaded out of the threaded portion 12 of the way 11 and that the ordinary rocker and tappet arms are lifted up from out of engagement with the valve stems.

75 In case it is desired to slightly grind the valve seats the tool is placed in position and as heretofore described the screws 28 and 29 are adjusted slightly to lift or pull the valve 15 into tight engagement with the seat after which the wrench or key 40 can be rotated several times which will of course loosen any carbon between the valve and its seat. If desired kerosene can be used 80 for loosening carbonized and sticky cages when the valves are being temporarily ground, the retaining rings for the cages not being removed.

85 From the foregoing description, it can be seen that an improved tool has been provided for pulling valve cages of overhead valves which is of simple and durable construction, and which will permit the convenient and expeditious removing of the 90 valve cage.

95 Changes in details may be made without departing from the spirit or scope of this invention.

100 What we claim as new is:—

105 1. A valve puller comprising a puller plate embodying end portions and a connecting arcuate body arranged to extend around the valve stem and spring, means carried by the plate for engaging the ordinary valve spring washer, adjustable members carried by the plate adjacent the ends thereof, and bearing means for engaging the lower ends of said adjustable members and the cylinder 110 adjacent to the valve to be pulled.

115 2. The combination with a cylinder head having a way therein, a valve cage in said way and a valve stem and body carried by the cage, a washer and spring on said stem, of a valve cage pulling tool comprising a 120 puller plate adapted to encircle the valve stem and spring and arranged to engage the lower surface of the washer and the upper edge of said spring, bearing means arranged to engage the upper end of the cylinder head and adjustable members carried by the puller plate arranged to engage said bearing means.

125 3. A valve cage lifter and valve grinding tool comprising a bearing device adapted to 130

engage the upper end of a cylinder head, a puller plate, means formed on the puller plate for engaging between the valve spring washer and spring, and adjustable cap screws carried by the puller plate arranged to engage the bearing device.

4. A valve cage pulling tool comprising an arcuate bearing plate having sockets formed in the upper surface thereof, a puller plate, adjustable cap screws carried by the puller plate adjacent to each end thereof, ball ends formed on the lower terminals

of the cap screws for engaging in the sockets, an arcuate shoulder formed on said puller members, and inclined lower leading faces ¹⁵ formed on the forward ends of the shoulder at the lower surface thereof.

In testimony whereof we affix our signatures in presence of two witnesses.

JAMES M. HARRUE.
HOMER N. TYSON.
